Patented Dec. 16, 1958

184,095

FLASH UNIT FOR PHOTOGRAPHIC CAMERAS

Clark C. Macomber, Evanston, Ill., assignor to Bell & Howell Company, Chicago, Ill., a corporation of Illinois

Application September 19, 1958, Serial No. 52,691

Term of patent 14 years

(Cl. D61—1)

FIG. 1.

FIG. 2.

Figure 1 is a perspective view of a flash unit for photographic cameras embodying my new design; and

Figure 2 is another perspective view of the same showing the sides thereof opposite those shown in Figure 1.

I claim:

The ornamental design for a flash unit for photographic cameras, as shown.
